UNITED STATES PATENT OFFICE.

JOHN COLLINS CLANCY, OF NIAGARA FALLS, NEW YORK, ASSIGNOR TO THE NITRO-
GEN CORPORATION, OF PROVIDENCE, RHODE ISLAND, A CORPORATION OF RHODE
ISLAND.

PROCESS FOR PRODUCING GASOLINE AND THE LIKE.

1,423,709.

Specification of Letters Patent. Patented July 25, 1922.

Application filed July 31, 1919. Serial No. 314,434.

To all whom it may concern:

Be it known that I, JOHN COLLINS CLANCY, subject of the King of Great Britain, residing at Niagara Falls, in the county of Niagara and State of New York, have invented 55 certain new and useful Improvements in Processes for Producing Gasoline and the like, of which the following is a specification.

10 This invention relates to a process for cracking hydrocarbons, and has for one of its objects the provision of a method capable of converting kerosene, or the like, into more highly volatile substances, such as gasoline.

15 Another object of the invention is to secure a higher percentage of conversion of the heavier hydrocarbons into lighter hydrocarbons having lower boiling points, than, to the best of my knowledge, has hitherto 65 been possible,—at least in one operation.

20 I further aim to utilize a volatile catalyst in said conversion, in such fashion as to avoid substantial waste or loss of such catalyst.

25 These and other objects of my invention, —such as improved product,—will be hereinafter referred to and the novel combinations of steps which constitute the improved process will be more especially pointed out 70 in the appended claims.

30 In the drawing which forms part hereof, I have diagrammatically exemplified a preferred apparatus in which my process may be effectuated; but as I am aware of various 75 changes and modifications which may be made in said process and apparatus, without departing from the spirit of my invention, I desire to be limited only by the scope of said claims, broadly considered in the light of my 80 disclosure.

In said drawing:

35 The figure shows, diagrammatically, an exceedingly simple apparatus in which, preferably, kerosene may be converted into 85 gasoline.

40 In said apparatus the vapor of a hydrocarbon to be treated, e. g. kerosene, passed up via pipe 1 from a suitable source of such vapor, such as a still 2. Pipe 1 is preferably 90 made to serve as a mixing chamber; steam, air, or an equivalent oxygen supplying medium, being introduced into said chamber

through a pipe 3. As steam, acting conjointly with the vaporous catalyst, tends to afford a higher yield of high grade gasoline, 55 I prefer steam to air. It also tends to reduce the formation of the olefines and deposition of carbon; although when using my novel catalyst, I find little of this latter, especially when an adequate supply of oxygen is afforded; the oxygen combining with the excess 60 carbon to form carbon monoxid.

I do not wish to be limited to the employment of an oxygen supplying medium in my process; since the vaporous catalyst is capable of performing its function even when oxygen is not present. I greatly prefer, however, to supply an adequate amount of oxygen, for reasons above noted.

70 The mixture of, let us say, kerosene vapor and steam is quite complete by the time that it emerges from pipe 1 into the reaction chamber 4. This latter may conveniently be formed of a pipe of considerably larger diameter than that designated 1.

75 To the lower end of pipe 4 is fastened a receptacle 5; the jointure between said receptacle and pipe being gas-tight and the receptacle being, further, preferably covered with heat insulation 6,—e. g. magnesia, asbestos, or the like.

80 Within the receptacle 5 is a heating element 7, of any suitable description, although I prefer to use an electrically heated element 85 for this purpose. The leads to said element have been designated 8 and 9, and as the construction of such resistance heating devices is well known, it need not herein be considered in detail.

85 Within the receptacle 5, and preferably 90 surrounding and in contact with the heating element 7, is a mass of liquid mercury 10, which, during the course of the process, normally volatilizes gradually, since it is heated by the element 7 to approximately 95 400° C., or somewhat higher.

100 The vapor of mercury passes up and mixes intimately with the mixture of hydrocarbon vapor and steam, aforesaid, and the new mixture, thus formed, then passes up through a superheating zone 4' in the pipe 4, in which the mercury-enriched vapor becomes heated preferably to about 600° C., if gasoline is the product sought. If still

lighter hydrocarbons are to be formed, the temperature is correspondingly raised.

The reaction proceeds vigorously in the superheating zone and gradually abates as

- 5 the gaseous mixture flows thence up through the cooling section 4' of pipe 4. By the time that the gases reach the upper end of pipe 4, much of the mercury vapor has condensed; but as it settles down by gravity 10 into the superheating zone, it again volatilizes and reascends with the incoming hydrocarbon vapor, to thus continue to circulate in pipe 4 as long as the process is conducted in the manner described.
- 15 The hydrocarbon vapor, now rich in gasoline, passes over, together with some mercury vapor, through pipe 11 into the condenser 12, in the coil 12' of which, the remaining mercury vapor is liquefied.
- 20 Of course, some mercury will be condensed in pipe 11 and most of this will flow back into pipe 4; while the liquid mercury formed in coil 12' will flow down into the trap 13 and thence back by way of pipe 14 to the receptacle 5.

The gasoline and other light hydrocarbons are cooled sufficiently to free them from mercury, and, if desired, from most of the residual heavy hydrocarbons which, for 30 any reason have not been sufficiently reacted upon by the catalytic mercury vapor. Such heavy hydrocarbons will flow, along with the mercury, via the return pipe 14 to receptacle 5, in which they will normally promptly be volatilized for return to the process.

The condenser may be sufficiently cooled by air or other suitable cooling fluid; the cooling medium passing into the casing 12 through pipe 15 and out through pipe 16. Care 40 should be exercised to avoid undue cooling of pipe 12', however, since in such case obviously a part of the lighter hydrocarbons might be condensed and uselessly returned to the process via pipe 14. The temperature to be maintained in the gas passing off, from the trap through pipe 17, will depend upon the product desired and also, of course, upon the pressure at which the operation is conducted.

50 Pressure favors the efficient reaction of the vaporous catalyst upon the heavier hydrocarbons. Then, too, in a relatively small and inexpensive apparatus, with a condenser of but moderate size, the cracking operation 55 may be conducted at a higher temperature, since the increase in pressure substantially correspondingly raises the boiling point of the mercury and, of course, the temperature at which it condenses.

60 In addition, high pressure favors the return of insufficiently cracked hydrocarbons to the process via pipe 14.

When the operation is not conducted under sub-atmospheric pressure (and I prefer 65 to increase rather than decrease the pres-

sure, although even sub-atmospheric pressures may be employed) the temperature to be maintained in the receptacle 5 will in any case have to be above the boiling point of mercury to wit, 357.33° C., and it is desirable to not greatly exceed 600° C., in the superheating zone 4', although as high as from 650° to about 700° C., may be reached, especially if the operation be conducted under relatively high pressure.

75 The provision of the superheating zone 4', favors the condensation of the mercury returned through pipe 14, in that the temperature maintained in said receptacle is not so greatly in excess of the boiling point of 80 the mercury at the given pressure.

The superheating zone 4 may be constituted by surrounding pipe 4 at this point by a muffle 18, preferably of heat resistant material; a torch 19, or its equivalent, being 85 employed as the source of heat. When a torch is used, the gases of combustion escape from the muffle by way of pipe 20.

The general course of the preferred mode 90 of conducting the process may now be briefly reviewed: Vaporous kerosene is supplied from, for example, a fire still; steam or air being admixed with this vapor, preferably, although not necessarily, after the kerosene vapor has left the still. Mercury 95 vapor, ascending from the receptacle 5, is then mixed with the previous mixture and the whole vaporous mass is subjected in the superheating zone 4', to a temperature, preferably approximating 600° C., the vapor desirably being under a pressure of, 100 for example, ten atmospheres.

At this temperature the heavier hydrocarbons tend to crack and the hot mercury vapor present in most intimate contact therewith, acts most efficaciously as a catalyst, 105 both to crack the heavier oils and to enable the hydrogen afforded by the steam (or supplied in any other manner desired),—and that resulting from the cracking of said 110 heavier oils,—to hydrogenate the unsaturated hydrocarbons present to light naphtha and gasoline.

It is noteworthy that the gasoline produced by this simple operation is clear and 115 substantially free from the offensive odor which usually characterizes "cracked" gasoline and which requires additional treatment with sodium, or the like.

A further noteworthy feature is that 120 whereas when aluminium chlorid is used as a catalyst for cracking oils, in a known manner, it loses its efficacy within a comparatively short time and becomes converted into a black coke-like mass,—in the present 125 process the deposition or formation of carbon deposit, or coke, is so small, when the operation is conducted in the preferred manner herein described, as to be substantially negligible; and, in any case, even when car- 130

bon deposits form,—as may occur, especially when cracking heavier hydrocarbons than kerosene,—the catalyst can readily be recovered by distilling the mercury from the 5 so formed "coke."

Moreover, the yield of the desired light hydrocarbons is extraordinarily high, as much as 60% or more of the kerosene supplied to the process being converted into 10 clear, high grade gasoline, the olefine content of which is normally low, as a result of the potency of my novel catalyst in favoring the hydrogenation of the light unsaturated hydrocarbons by the free hydrogen 15 present under the described conditions.

I accordingly do not wish to be limited merely to the cracking of hydrocarbons, since in certain phases of my process hydrogenation is involved and in general the 20 product to be formed will depend upon the temperature and pressure employed, and, of course, to a considerable measure, the molecular constitution of the hydrocarbon or hydrocarbons initially supplied to the process.

25 Having thus described my invention, what I claim is:

1. The process of cracking hydrocarbons, which comprises subjecting a hydrocarbon oil, while in vaporous condition, to the catalytic action of mercury vapor.

2. The process of cracking hydrocarbons, which comprises subjecting a hydrocarbon oil, while in vaporous condition, to the action of mercury vapor, condensing said mercury vapor and separating the mercury from 35 the hydrocarbon product formed.

3. The process of cracking hydrocarbons, which comprises subjecting the hydrocarbon to be treated, to the action of heat while in 40 the presence of mercury vapor and steam.

4. The process of cracking hydrocarbons, which comprises subjecting vaporous kerosene to the catalytic action of vaporous mercury, at a temperature approximating a low 45 red heat.

5. The process of cracking hydrocarbons, which comprises subjecting vaporous kerosene to the action of vaporous mercury, condensing said mercury and returning it to 50 the process.

6. The process of changing the molecular constitution of a hydrocarbon, which comprises subjecting said hydrocarbon to heat

in the presence of mercury, vapor acting as a catalyst.

7. The process of changing the molecular constitution of a hydrocarbon, which comprises subjecting said hydrocarbon to a temperature above 357° C. and below 700° C., 55 in the presence of mercury.

8. The process of changing the molecular constitution of a hydrocarbon, which comprises subjecting said hydrocarbon, while under super-atmospheric pressure, to a temperature above 357° C. and below 700° C., 60 65 in the presence of mercury.

9. The process of cracking hydrocarbons which comprises subjecting said hydrocarbons while under pressure to the catalytic action of mercury vapor.

10. The process of cracking hydrocarbons which comprises heating said hydrocarbons under pressure in the presence of mercury vapor and steam.

11. The process of cracking hydrocarbons 75 which comprises vaporizing said hydrocarbons and causing the hydrocarbon vapors to mingle with mercury vapor while traversing a passage the temperature of which is higher than the boiling point of mercury.

12. The process of cracking hydrocarbons which comprises subjecting said hydrocarbons to the catalytic action of mercury vapor at a temperature above the normal boiling point of mercury.

13. The process of cracking hydrocarbons which comprises subjecting said hydrocarbons to the catalytic action of mercury vapor under pressure and at a temperature above the normal boiling point of mercury.

14. The process of changing the molecular constitution of a hydrocarbon which comprises subjecting said hydrocarbon to heat in the presence of hydrogen and mercury vapor.

15. The process of changing the molecular constitution of a hydrocarbon which comprises subjecting said hydrocarbon, while under super-atmospheric pressure, to the action of hydrogen and mercury vapor.

In testimony whereof I have affixed my signature, in the presence of two witnesses.

JOHN COLLINS CLANCY.
